UNITED STATES PATENT OFFICE.

JOHN C. DUEBER, OF NEWPORT, KENTUCKY.

PROCESS OF MAKING WATCH-CASE CENTERS.

SPECIFICATION forming part of Letters Patent No. 295,156, dated March 18, 1884.

Application filed November 15, 1883. (No model.)

To all whom it may concern:

Be it known that I, JOHN C. DUEBER, a citizen of the United States, residing at Newport, in the county of Campbell and State of Kentucky, have invented certain new and useful Improvements in Processes of Making Watch-Case Centers, of which the following is a specification, reference being had therein to the accompanying drawings.

10 My invention comprises a novel method or process of constructing those watch-case centers which are made of rolled-gold plate, the object of the improvement being to produce such "centers" in a neater and more uniform manner and at less cost of manufacture than is possible with any of the ordinary processes employed at the present time. This process consists in making the center of three separate parts—to wit, a ring or annulus and two other members, termed the "front" and "back" halves, said ring being provided either with an external or internal thread for the engagement of suitable threads cut on said front and back halves. Consequently when these 25 halves are screwed into or around said ring the watch-case center is practically as firm and durable as though it were made of a single piece of metal; but to prevent any intentional separation of these three component members of the 30 center they may be soldered or otherwise fastened together. One convenient way of uniting them would be to apply solder or rivets at the place where the "pendant-bearing" is secured.

In the annexed drawings, Figure 1 is an axial section of the blank employed for producing the front and back halves of a watch-case center. Fig. 2 is a similar section of the three different members of the center in one stage of manufacture. Fig. 3 is an axial section, showing the front and back halves screwed into the ring. Figs. 4 and 5 are enlarged transverse sections of two different modifications of my invention.

Referring to Fig. 1, A represents a blank, 45 which is first cut out of rolled-gold plate, and then brought to the desired shape by being struck up in an ordinary forming or shaping press. The plate is made in the usual manner by rolling one or more sheets of gold onto a 50 sheet of base metal, although the blank A may in some cases be composed of pure gold or other suitable metal. Furthermore, said blank is of

such a diameter and thickness as to produce either the front half, B, or the back half, C, (seen in Fig. 2,) said members B C being provided with the customary annular flanges, shoulders, or snaps, and also with cylindrical necks b c, which latter are formed by properly turning down said blank.

D represents a ring or annulus, that constitutes the inner or intermediate member of the center, said ring being somewhat thicker than the halves B C, and being preferably knurled, chased, or otherwise ornamented on its outer periphery, as at d. This ring may be spun up; 60 but the better plan is to make it with a die and shaping-press, so as to insure the utmost uniformity of manufacture. After these three component members B C D have been brought to the desired shape, male threads are cut on 65 the cylindrical necks b c, and a female thread is chased within the inner periphery of ring D. Said halves B b C c are now screwed into the ring D, as seen in Fig. 3, which simple operation completes the construction of the center 70 and leaves it ready for the application of the pendant, the fitting of the hinges, &c.

As a watch-case center is seldom, if ever, subjected to a twisting action, there is no danger of either of the members B or C being 80 screwed out of the ring D; but to prevent said halves being intentionally disengaged they may be soldered in place or be secured with rivets or other fastenings. As previously stated, the pendant-bearing can be soldered to 85 these halves, thereby rendering it impossible for the center to come apart until said bearing is unsoldered.

As all the various members of the center can be made with ordinary dies and shaping- 90 presses, it is evident said parts will not require skillful workmen to produce them, but can be manufactured by boys in the most rapid and uniform manner. Furthermore, as the junctions of the halves B C with the ring D 95 occur circumferentially around the center, they will not be perceptible.

As the leading feature of the present process consists in making watch-case centers of three component members and screwing them together, I do not propose to limit my claim to specific details of construction, provided this novel feature of the screw-coupling is retained. One modification is seen in Fig. 4, where the

front half, B, is screwed into the ring D, and the back half, C, is engaged with a female thread cut within the annular rim of said member B; but in Fig. 5 the ring D is internal, and 5 the halves B C are provided with female threads that engage with a male thread cut on the outer periphery of said ring, the junction or parting of said halves being concealed by the subsequent burnishing or finishing operation or operations. Finally, the exact proportions of a watch-case have not been shown 10 in the drawings, the screw couplings or joints having been intentionally enlarged to render them clear, and the central portion of the case 15 being broken away.

I claim as my invention—

The within-described process of making watch-case centers, which process consists in forming said center of a ring and a pair of "halves," and then screwing together these 20 three component members, substantially as herein described and set forth.

In testimony whereof I affix my signature in presence of two witnesses.

JOHN C. DUEBER.
